UNITED STATES PATENT OFFICE.

FRANKLIN D. PECK, OF ELKHART, INDIANA, ASSIGNOR OF TWO-THIRDS TO
S. S. LONGACRE AND J. A. S. LONGACRE, OF SAME PLACE.

MACHINE FOR MAKING PAPER PAILS.

SPECIFICATION forming part of Letters Patent No. 341,163, dated May 4, 1886.

Application filed February 8, 1886. Serial No. 191,217. (No model.)

To all whom it may concern:

Be it known that I, FRANKLIN D. PECK, a citizen of the United States, residing at Elkhart, in the county of Elkhart and State of Indiana, have invented new and useful Improvements in Machines for Making Paper Pails, of which the following is a specification, reference being had to the accompanying drawings.

10 My invention relates to improvements in machines for making paper pails; and it consists of the peculiar and novel construction and combination of parts, substantially as hereinafter fully set forth, and specifically pointed 15 out in the claims.

The objects of my invention are to provide improved means for conveying the pulp from a receptacle to the proper forms on which the pails are first made, and which at the same 20 time shall permit of the proper discharge of surplus water or other fluid that is forced from the pulp; to provide improved means for conveying the pulp from the receptacle to a traveling carrier; to provide forms of the proper 25 configuration that are readily and quickly removable, to be replaced by other forms of similar construction; to provide means for exerting the proper requisite pressure on the forms to compress the pulp very firmly and 30 compactly, and at the same time force any surplus water or other fluid from the pulp; to provide means that shall be conveniently operated to release the pressure-rolls from bearing and pressing on the forms when the latter 35 are to be removed; to provide means for positively rotating the pressure-rolls; to provide troughs for conveying and discharging the water or other fluid pressed from the pulp by the pressure-rolls, and to provide means that are 40 simple and strong in construction and thoroughly effective and reliable in operation.

I attain the above-named objects by the mechanisms which are illustrated in the accompanying drawings, in which—

45 Figure 1 is a side elevation of a machine for making paper pails, constructed in accordance with my invention. Fig. 2 is a horizontal sectional view on the line xx of Fig. 1. Fig. 3 is a transverse vertical sectional view on the 50 line yy of Fig. 2. Fig. 4 is a longitudinal sectional view on the line zz of Fig. 2. Fig. 5 is a detail view of one of the removable forms

with its standard and frame, and Fig. 6 is a similar view of the pressure-roller and the means for elevating and depressing the same. 55

Referring to the drawings, in which like letters of reference indicate corresponding parts in the several figures, A designates supporting uprights or columns that are suitably disposed and arranged to support a cover or roof, 60 a , to protect my improved machine and provide for suspending or holding hangers of the pressure-rollers, as will more fully appear presently.

B designates a receptacle or vessel, of any 65 preferred form and dimensions, to receive the pulp from which the pails are to be formed, the pulp being made before it is deposited in the receptacle.

C designates a roller that is arranged to revolve in the pulp-receptacle B and convey the pulp therefrom to a traveling carrier, D, that rotates in a horizontal plane around a rotatable center and supplies the forms E with pulp from the receptacle B. This conveying-roller 70 75 C is rigidly mounted on a shaft, c , that is journaled in proper bearings on the receptacle B. One end of this shaft c is extended beyond the receptacle B, and receives a pulley, crank, or other suitable mechanical device for rotating 80 the shaft from a motor or other source of power, and the other end of this shaft, which, for convenience, I will term the "driving-shaft," carries a spur gear-wheel, c' , that meshes with a rack, d , on the traveling carrier D. 85

The traveling carrier D is made circular in form, and it comprises an inner and outer ring, d^1 , d^2 , to which are secured the edges of an intermediate canvas or other fabric section, d^3 , that is stretched and held taut on the rings or 90 open frame. The inner ring, d^2 , is provided on its under and upper surface with teeth or cogs, that constitute the racks d , and said inner ring of the carrier has radial arms d^4 , which meet at a common center and are rigidly secured 95 or keyed upon a vertically-disposed shaft, d^5 , which is journaled at its ends in bearings D' , D^2 . The bearing D' is rigidly held in place on the floor, ground, &c., and the bearing D^2 is formed in or rigidly affixed to a cross-beam, 100 D^3 , that is supported at its ends on columns or uprights D^4 . In lieu of supporting the shaft d^5 in the beam D^3 , the latter and its columns may be dispensed with and the upper end of

the shaft d^5 journaled in a proper bearing properly affixed to the cover or roof a . The traveling carrier D is thus composed of an open-geared frame and fabric section, and the 5 carrier is disposed in an approximately horizontal position, so that one edge thereof shall be lower than the other edge that lies diametrically opposite therefrom, or the carrier may be said to occupy a horizontally-inclined position and to rotate in a horizontal plane.

The conveying-roller C bears against the lower under face of the canvas or fabric section of the open frame of the traveling carrier, and the pulp from said conveying-roller adheres to the canvas or fabric of the traveling carrier until it comes in contact with the periphery of the forms E , to which it adheres to form the body of a pail. These forms E are shaped to correspond to the curvature or inclination of the vessel or pail body which is to be formed thereon, and in the present instance I have shown said forms E in the shape of a frustum of a cone with their smaller diameters on the inner end or nearest the center of 25 the rotatable traveling carrier D . The inclination or angle of the carrier D corresponds to the inclination of the forms E , so that the peripheries of the latter can bear equally at all points against the fabric section of the carrier to distribute the pulp evenly and uniformly on the forms, and the conveying-roller C is also made frustum-shaped, to uniformly apply the pulp to the fabric of the traveling carrier D .

35 In the drawings I have shown two forms E ; but it will be understood that three or more may be employed if it is deemed desirable.

Where only two forms are provided for the machine they are used one at a time—that 40 is to say, when the form of standard No. 1 is in use or receiving pulp from the carrier, the form of standard No. 2 is removed or out of contact with the carrier, and vice versa, as it will be readily seen that if both are allowed 45 to remain in use the form of standard No. 1 will take up all or nearly all of the pulp from the carrier, and the form of standard No. 2 will receive a very meager or no supply at all. I have also provided and arranged 50 means whereby both forms can be allowed to remain in their standards and to bring or adapt the carrier to supply either one of the forms with pulp, which devices and their operation will be presently described.

55 The rollers or forms E and their standards are disposed beneath the elevated or higher end of the horizontally-rotatable carrier, and the carrier is normally elevated above and out of contact with the peripheries of the forms. 60 Each form is provided at its ends or heads with pins or studs e , which are loosely mounted in proper bearings, f , which are secured to or cast with a frame, F , that is arranged to slide vertically in grooves or recesses g of standards 65 G , which are connected at their lower ends. These vertically-sliding frames F and their fixed standards G are of any suitable form or

construction, and the forms E are loosely mounted in the bearings of the frame, to adapt them to be readily detached or removed and interchanged, after they have been supplied with pulp, with forms of similar construction that are to be filled with pulp. The sliding frames are adapted to be elevated to any suitable height to bring the forms into proper juxtaposition to and contact with the fabric section of the carrier D , and when the frame and form have been properly elevated and adjusted they are rigidly held in place by means of a catch, h , that enters a notch or socket in 70 the frame, or by any other suitable or preferable means. The frustum-shaped forms are rotated by frictional contact with the periphery of a rotating pressure-roller that bears on the canvas section of the carrier, and it will 75 be readily seen that when the carrier is in motion it will apply the pulp to the form, and at the same time the form will be rotated by the rotatory pressure-roller, which evenly and uniformly applies the pulp to all parts of the form 80 throughout its entire periphery. After the form has been covered or coated with the pulp to the required thickness it is lowered and removed from the frame, without stopping or otherwise interfering with the motion of the 85 machine, and its place supplied by another 90 machine, and its place supplied by another form of similar construction.

Each form is acted upon by a pressure-roller, I , that is suspended above the fabric section of the traveling carrier and serves to compress the pulp very firmly and compactly on the form. The pressure rollers are made frustum-shaped to correspond with the angle of the form and the inclined rotatable carrier D , and the conveying-roller C also has a pressure- 100 roller, I' , bearing thereon with sufficient force to cause the pulp from the conveying-roller to adhere to the carrier D ; but the force which the roller I' exerts on the roller C is regulated so that it is considerably less than the pressure 105 of the rollers I on the forms E .

The rollers I and I' are each provided at their ends with studs or pins i , which are free to move in slots j , that are formed in vertically-disposed arms j' of hangers J , which are 110 suspended from the cover or roof a . The hangers may be of any suitable construction, and the lower ends of the slots j may be left open and carry a removable pin, j'' , whereby the pressure-rollers can be readily removed.

I will now proceed to describe my preferred form of device for regulating the pressure on the pulp and form.

A yoke, K , is connected loosely to the studs i of each of the rollers, to permit them to 115 turn freely, and to a lug, k , of this yoke is pivoted a lever, L , which extends through and is pivotally supported within a slotted portion, l , of one of the arms j' of the hanger J . A similar lever, M , is pivoted at or near its middle to 120 a suspended rod, m , and one end of this lever is pivoted to the free end of the lever L , and to the opposite end of the lever M is pivoted a link, N , which connects with an operating han-

dle-lever, O, which is pivoted at one end to a standard, o, and has a tooth, o', adapted to engage and be retained by one of a series of teeth on a rack-bar or standard, O'. This handle-lever O is normally held down by a coiled spring, o², or by a weight, so that the pressure of the pressure-roller can be varied. It will be seen that when the free end of the spring-actuated pivoted handle-lever is elevated the connected ends of the pivoted levers L M will be depressed and the inner end of the lever L will be elevated, to raise the bracket or yoke K and the pressure-roller, and when the free end of the handle-lever is depressed the pressure-roller will be lowered, to bear against the traveling carrier, the degree of elevation or depression depending upon the amount of movement of the handle-lever, as will be readily understood.

Each of the pressure-rollers I is positively rotated by motion transmitted thereto from rotatable traveling carrier D, through a pinion, P, rigidly secured to the extended inner stud of the pressure-rollers I, and meshing 25 with the teeth or cogs of the rack-bar on the upper surface of the rotatable carrier.

Q designates troughs, that are arranged parallel with the pressure-rollers I and transversely across the traveling carrier, and this trough is suspended above the traveling carrier by means of rods or cords q. The troughs are to receive and discharge the water or other fluid that is forced from the pulp through the porous fabric or canvas of the traveling carrier 35 by the pressure-rollers and to convey the same away from the forms, to prevent the pulp thereon from becoming too wet, and thus they can be more quickly dried.

When the forms E are elevated to bring them into operation, they bear against and elevate a portion of the flexible fabric of the traveling carrier, so that the fabric is inclined for a portion of its length, and as the pressure-roller forces the surplus water from the pulp the water will permeate through the fabric and descend the inclined portion of the fabric, and flow into the discharge trough or spout, by which it is conveyed from the carrier and the form. The inclined discharge-spout is suspended above the traveling carrier, and its open side is arranged to bear on the fabric of the carrier, whereby, when the latter is elevated by the form to produce the incline, the water from the pulp will readily enter the trough.

Each of the troughs is provided with an inclosing-wall around its several edges, except at the part or side that lies alongside of the pressure-roller, which is left open, so that the water, &c., can pass into and through the trough, and one end of the trough or discharge-spout is contracted and extended beyond the edges of the carrier, to convey the water therefrom and discharge it into proper receptacles, the troughs being arranged in an inclined position, to more effectually discharge the water.

Q' designates a similar discharge-spout for

the pressure-roller I', that is suspended and disposed in an inclined position, one end thereof being left open to receive the water 70 that is forced through the fabric section of the carrier by the rollers C and I'.

The operation of my invention is as follows: The pulp, which has already been prepared, is poured or otherwise discharged 75 into the receptacle or hopper B and the pressure-roller I' adjusted to bear on the conveying-roller C to the proper degree, the force thereof being regulated, so as to only press a portion of the water from the pulp 80 and to cause the pulp to adhere to the carrier. One of the forms E is adjusted or elevated to bear against the fabric section of the carrier, and the pressure-roller I lowered to bear on said canvas section of the carrier above the 85 latter and the form, after which power or motion is communicated to the driving-shaft c. The roller C is thus revolved to convey pulp from the reservoir or receptacle B to the traveling carrier, which conveys it to the form E, 90 where it is discharged onto the latter. Simultaneously with the rotation of the conveying-roller C the horizontally-rotatable traveling carrier D is revolved, and the motion there-of is transmitted to the form E and pressure- 95 roller I by frictional contact between the form and pressure-roller and the gearing d P. The positively rotated pressure-roller serves to rotate the form by bearing thereon, and to press the surplus water from the pulp through 100 the canvas, and it then passes into the discharge-spout or trough Q, and at the same time the pressure-roller compresses the pulp compactly and firmly on the form E. When the form E is coated with pulp to a sufficient thickness, the pressure-roller I that bears thereon is elevated by elevating the handle-lever O and the sliding frame F lowered, after which the form with the pail thereon is removed and its place supplied with another form of similar construction. Simultaneously with the elevation of one pressure-roller and the depression of the form that coacts therewith another pressure roller and form are adjusted for use, and this operation is continued without 115 requiring the stopping of the machine.

It will be observed from the foregoing description, taken in connection with the drawings, that I provide a machine which compresses the pulp very firmly and compactly 120 on the form of required shape, and that the latter is readily interchangeable without stopping the motion of the machine. I provide for the proper supply of the pulp and the discharge of surplus water, and also regulate the 125 pressure on the forms, so that a greater or less quantity of pulp can accumulate thereon, while at the same time the pulp is evenly and uniformly applied throughout all points on the periphery of the form.

I do not desire to limit myself to the details of construction and form and proportion of parts herein shown and described as an embodiment of my invention, as I am aware that

many changes may be made without departing from the principle thereof.

I am aware that it is not broadly new to employ a horizontal rotatable carrier having a sieve, a forming-roller bearing on the upper surface of the carrier and mounted in a vertically-movable frame fitted in proper standards, and a pressure-roller on the under side of the carrier beneath the forming-roller and having a rack which meshes with a pinion on a hand-shaft to adjust the pressure-roller vertically.

I am also aware that it is not new to employ a centrally-supported horizontal felt-carrier which rotates about its axis and is inclined, a trough in which works a conveying-roller to transfer the pulp to the felt-carrier, a pressure-roller to the conveying-roller, a supplemental frame pivoted centrally to the main frame and carrying a forming-roller at each end, the frame being rotatable on its shaft to bring either roller in contact with the felt-carrier, a pressure-roller to the forming-roller, and a shaft having belts to rotate the pressure-rollers.

Having thus described my invention, what I claim as new, and desire to secure by Letters Patent, is—

1. The combination of a traveling carrier, a rotatable form in contact with the carrier and receiving its charge therefrom, and a positively-rotated pressure-roller geared to and actuated by the carrier and bearing thereon, and the form to rotate the latter, substantially as described.

2. The combination of a carrier, the pressure-rollers, the standards 1 and 2, having the adjustable forms mounted therein and alternately thrown into and out of contact with the carrier, substantially as described.

3. The combination of a carrier, the pressure-rollers, the standards 1 and 2, vertically-sliding frames, forms loosely and detachably mounted in the frames and adjustable alternately in contact with the carrier, and means for locking the forms and the frames in their adjusted positions, substantially as described.

4. In a machine for making paper pails, the combination of a traveling carrier, a rotatable form, a pressure-roller, and means for adjusting the pressure-roller and maintaining the same to any desired adjustment and pressure on the carrier and form, substantially as described.

5. In a machine for making paper pails, the combination of a traveling carrier, a rotatable form, a vertically-adjustable pressure-roller, and means for varying the force of the pressure-roller on the form and carrier, substantially as described.

6. The combination of a carrier, a rotatable form, a vertically-adjustable pressure-roller, a yoke having the roller suspended therein, pivoted levers for adjusting the roller, and a handle-lever connected with the pivoted levers for actuating the latter, substantially as described.

7. In a machine for making paper pails, the combination of a traveling carrier, a vertically-movable frame supported and arranged below the carrier, a form detachably mounted in the frame and adapted to be held in contact with the carrier, and a pressure-roller, substantially as described. 7c

8. In a machine for making paper pails, the combination of a traveling carrier, a grooved standard, a vertically-movable frame sliding in the standard, a rotatable form detachably mounted in the frame, and a latch for retaining the frame and form in their elevated position, substantially as described. 75

9. The combination of a traveling carrier, a receptacle, a driving-shaft geared to the carrier for actuating the same, and a conveying-roller mounted on the shaft and having its periphery in contact with the carrier, substantially as described. 80

10. The combination of a receptacle, a traveling carrier, a driving-shaft for actuating the carrier, a conveying-roller mounted on the shaft, and a pressure-roller, substantially as described. 90

11. The combination of a receptacle, a traveling carrier, a driving-shaft geared to the carrier, a conveying-roller mounted on the shaft and working within the receptacle with its periphery in contact with the carrier, a vertically-adjustable pressure-roller, and means for varying the pressure of the pressure-roller on the form, substantially as described. 95

12. In a machine for making paper pails, the combination of a traveling carrier, a pressure-roller, and a trough for receiving and discharging the water pressed from the pulp by said roller, substantially as described. 100

13. In a machine for making paper pails, the combination of a traveling carrier, a pressure-roller, a form, and a suspended trough disposed parallel with the pressure-roller for conveying the water therefrom extracted from the pulp, substantially as described. 105

14. In a machine for making paper pails, the combination of the following elements: a receptacle, a conveying drum or roller working therein, a driving-shaft on which the conveying-roller is mounted, a geared horizontally-rotatable carrier actuated by the driving-shaft, the adjustable forms adapted to be alternately operated and having their peripheries in contact with the carrier, a vertically-adjustable pressure-roller for each form and the conveying-roller and geared to the rotatable carrier, and a suspended trough, substantially as described. 115

In testimony that I claim the foregoing as my own I have hereto affixed my signature in presence of two witnesses. 120
